ATTORNEY

UNITED STATES PATENT OFFICE.

CHARLES ANDREW STURM, OF CASTLEROCK, WASHINGTON.

STEAM-BOILER.

No. 796,265.

Specification of Letters Patent.

Patented Aug. 1, 1905.

Application filed December 15, 1904. Serial No. 236,957.

To all whom it may concern:

Be it known that I, CHARLES ANDREW STURM, a citizen of the United States, and a resident of Castlerock, in the county of Cowlitz and State of Washington, have invented a new and Improved Steam-Boiler, of which the following is a full, clear, and exact description.

The object of the invention is to provide a new and improved steam-boiler which is simple and durable in construction, cheap to manufacture, and arranged to utilize the burning fuel to the fullest advantage and with a view to generate steam quickly and very economically.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement arranged as a stationary boiler. Fig. 2 is a sectional plan view of the same on the line 2 2 of Fig. 3. Fig. 3 is a longitudinal sectional elevation of the same. Fig. 4 is a transverse section of the same on the line 4 4 of Fig. 3. Fig. 5 is a sectional plan view of one of the cast-iron compartments; and Fig. 6 is a sectional side elevation of the same, the section being on the line 6 6 of Fig. 5.

The stationary steam-boiler shown in the drawings is built into a suitable brickwork A, supporting a bottom chamber or compartment B, having at its free end a cut-out portion B' for the reception of the grate C for the burning fuel in the fire-box. The bottom chamber B is connected by pipes D with an intermediate chamber or compartment E, which in turn is connected by pipes D' with a top chamber F, carrying a steam-dome G of any approved construction. The intermediate chamber E extends from the front H of the boiler to within a distance of the rear end or the back of the brickwork, as plainly illustrated in Fig. 3, and the rear portions of the bottom and top chambers B and F are connected with each other by pipes D'', extending through the space between the rear end of the intermediate chamber E and the back of the brickwork A. A horizontally-disposed partition I, preferably lined with asbestos or a similar material, extends in the brickwork between the chambers E and F, said partition

reaching from the back of the brickwork to within a distance of the front H of the boiler to direct the smoke and gases forwardly to a chimney J, leading from the front of the furnace, immediately below the top compartment F. Now by the arrangement described the smoke and gases arising from the burning fuel in the fire-box pass first rearwardly between the bottom chamber B and the intermediate chamber E, so as to heat the water contained in the said chambers, and then the smoke and gases rise at the rear end of the furnace until they strike the under side of the partition I to cause the smoke and gases to now travel forward between the said partition and the top of the chamber E. The smoke and gases finally rise in the front portion of the furnace to the under side of the steam-chamber F and then pass to the chimney J. The partition I prevents an overheating of the steam-compartment F.

By arranging the sets of pipes D, D', and D'' in the manner described it is evident that the water readily circulates through the several chambers or compartments, and as the smoke and gases come in contact with the several pipes and also with the chambers it is evident that the water is highly heated and quickly generated into steam, and the burning fuel is utilized to the fullest advantage.

The front H of the boiler is provided with the usual fuel-supply door H' and the ash-pit door H'', leading to the ash-pit K, arranged below the grate C.

The several chambers B E F are provided with suitable hand-holes to permit of obtaining convenient access to the chambers for cleaning the same whenever it is desired to do so. The top of the uppermost chamber F is provided with suitable plugs which when removed permit convenient access to the pipes or tubes D', D'', and D for cleaning the same whenever necessary. Other suitable accessories usual on boilers are supplied at the proper places, such as a water-gage, a steam-pressure gage, and the like.

The several chambers B, E, and F may be of cast-iron, boiler-iron, steel, or other suitable material, and the several chambers may be connected with each other by suitable stay-bolts, and each of the chambers may have its sides fastened together by stay-bolts, so as to prevent spreading of the chambers. If the chambers are made of cast-iron, (see Figs. 5 and 6,) then suitably-spaced strengthening-ribs X are employed, the ribs integrally con-

necting the top and bottom of the chambers with each other.

Having thus described my invention, I claim as new and desire to secure by Letters Patent—

1. A steam - boiler comprising a bottom chamber having a cut-out portion for the fire-box, a top chamber, an intermediate chamber extending from the front of the boiler to within a distance of the rear of the boiler, pipes connecting the bottom chamber with the intermediate chamber, pipes connecting the intermediate chamber with the top chamber, pipes connecting the top chamber with the bottom chamber in the rear of the said intermediate chamber, and a horizontal partition between the top and intermediate chambers and extending from the rear forwardly to within a distance from the front of the boiler.

2. A steam - boiler comprising a bottom chamber having a cut-out portion for the fire-box, a top chamber, an intermediate chamber extending from the front of the boiler to within a distance of the rear of the boiler, pipes connecting the bottom chamber with the intermediate chamber, pipes connecting the intermediate chamber with the top chamber, pipes connecting the top chamber with the bottom chamber in the rear of the said intermediate chamber, and a horizontal partition between the top and intermediate chambers and extending from the rear forwardly to within a distance from the front of the boiler at a point between the said top chamber and the said intermediate chamber.

3. A steam - boiler comprising a bottom chamber having a cut-out portion for the fire-box, a top chamber, an intermediate chamber extending from the front of the boiler to within a distance of the rear of the boiler, pipes connecting the bottom chamber with the intermediate chamber, pipes connecting the top chamber with the bottom chamber in the rear of the said intermediate chamber, a horizontal

partition between the top and intermediate chambers and extending from the rear forwardly to within a distance from the front of the boiler, and a steam-dome located above and connected with the said top chamber.

4. A steam - boiler comprising a bottom chamber, a top chamber, an intermediate chamber, a steam-dome carried by the top chamber, pipes connecting the bottom chamber with the intermediate chamber, pipes connecting the intermediate chamber with the top chamber, pipes connecting the top chamber with the bottom chamber, and a horizontal partition between the top and intermediate chambers and extending from the rear forwardly and terminating short of the front of the boiler.

5. A steam - boiler comprising a bottom chamber extending from the fire-box to the rear of the boiler, a top chamber extending from the front to the rear of the boiler, a steam-dome carried by the top chamber, an intermediate chamber extending rearward from the front of the boiler and spaced at its rear end from the rear of the boiler, pipes connecting the bottom chamber with the intermediate chamber, pipes connecting the intermediate chamber with the top chamber, pipes extending in the space at the rear of the intermediate chamber and connecting the top chamber with the bottom chamber, a horizontal partition extending forward from the rear of the boiler, and located between the top and intermediate chambers, and an outlet for the smoke and gases leading from the front of the boiler immediately below the top chamber.

In testimony whereof I have signed my name to this specification in the presence of two subscribing witnesses.

CHARLES ANDREW STURM.
